UNITED STATES PATENT OFFICE.

HARRY COHEN, OF MOUNT VERNON, NEW YORK.

DESIGN FOR A COMBINED DECANTER AND STAND.

Application filed May 16, 1924. Serial No. 9,629. Term of patent 7 years.

To all whom it may concern:

Be it known that I, HARRY COHEN, a citizen of the United States, residing at Mount Vernon, in the county of Westchester and State of New York, have invented a new, original, and ornamental Design for a Combined Decanter and Stand, of which the following is a specification, reference being had to the accompanying drawings, forming a part thereof, and in which—

Fig. 1 is a front elevation,
Fig. 2 a side elevation, and
Fig. 3 a top elevation of a combined decanter and stand embodying my design.

I claim:
The ornamental design for a combined decanter and stand, as shown.

HARRY COHEN.
